UNITED STATES PATENT OFFICE.

JOHN S. DUNLAP, OF PEORIA, ILLINOIS.

COUNTER.

SPECIFICATION forming part of Letters Patent No. 358,025, dated February 22, 1887.

Application filed November 20, 1886. Serial No. 219,443. (No model.)

To all whom it may concern:

Be it known that I, JOHN S. DUNLAP, a citizen of the United States, residing at Peoria, in the county of Peoria and State of Illinois, have 5 invented certain new and useful Improvements in Counters; and I do hereby declare that the following is a full, clear, and exact description of the invention, which will enable others skilled in the art to which it appertains to 10 make and use the same.

This invention relates to counters for stores.

The object of the invention is to produce a counter of such construction as to enable it to be made where material and labor are cheap, 15 and capable of being compactly packed for convenience in shipping; furthermore, the object of the invention is to produce a counter having a top which is capable of being vertically adjusted at will.

With these objects in view my invention resides, primarily, in a counter made of sections held in place by braces placed upon the outside and inside of the counter, the sections and braces being secured together by bolts or 25 screws in such manner that by removing the screws or bolts the counter may be packed in small space; furthermore, the invention resides in a counter having a top which is readily adjustable to change the height thereof.

I have illustrated the invention in the accompanying drawings, in which—

Figure 1 represents a perspective view of a counter made in accordance with my invention, a portion being shown in section in order to show the arrangement of parts. Fig. 35 2 is a sectional view showing the means for securing the parts together and for raising and lowering the top of the counter, and Fig. 3 represents a sectional view of a modified form of 40 device for regulating the height of the counter.

In the drawings, A represents a number of sections, preferably of wood, adapted to be placed one upon the other to form the front of a counter. The adjacent edges of these sections are formed at the proper angles to form 45 broad bearing-surfaces when paneled or other ornamental fronts are made. The preferred manner of securing the sections together in setting up the counter is by binding them between braces placed upon the outside and upon the inside of the counter. The outside or front brace is preferably ornamental, and

of such shape as to conform to the contour of the completed counter. In the present embodiment of the invention the pilasters B form 55 the outer brace, and the inner brace is formed by the place C, preferably of metal. For convenience in manufacture the pilaster is made, preferably, of cast metal, painted to correspond with the other exposed parts of the 60 counter.

The bolts D, which secure the sections in place and bind them between the braces, are so arranged as not to be visible from the front. This end is attained by embedding the head 65 of the bolt in a socket in the inner face of the pilaster and passing the shank through the section and the inner plate or brace, where it is secured by a nut.

The opening in the pilaster for the reception of the head of the bolt is large enough at the upper end, at d, to permit the introduction of the head of the bolt, and the lower portion is only wide enough to receive the shank of the bolt, so that by introducing the head of 70 the bolt and allowing it to drop down in the opening a firm fastening is provided.

Instead of introducing the head of the bolt into the opening in the pilaster, it may, when so desired, be embedded in one of the sections. So In this case the inner plate or base would be made of heavier material than when the parts were secured together in the manner first described in order to hold the sections firmly in place, and the pilaster would be attached by 75 85 nailing or in a similar manner.

When the counters are made in numbers, it is most convenient and economical to make the corresponding parts of the same size and dimensions. Different heights of counters are, 90 however, required in different situations, and it is therefore desirable that it be possible to raise and lower the top without disturbing the other parts of the counter. This is accomplished by providing the top of the counter 95 with depending projections E, which fit in sockets F, formed in the lower part of the counter, preferably the upper section. The lower end of the projections rest on the pins G, which may be placed in any one of the 100 holes g, in order to regulate the height of the counter.

Instead of the means just described for adjusting the top of the counter, I may utilize

the pawl-and-ratchet device shown in Fig. 3 of the drawings. In this form the projection from the counter is provided with notches h , which are entered by the end h^2 of the spring-
pawl h' , which projects far enough to form a handle for grasping in changing the position of the top.

Having thus described my invention, what I claim as new, and desire to secure by Letters Patent, is—

1. In a counter, the combination of a series of differently inclined sections placed one above another and having their contiguous edges approximately in contact, internal and external braces conforming substantially to the contour of said sections, and bolts connecting said external and internal braces, substantially as and for the purpose set forth.

2. A counter made up of a series of sections resting one upon the other and having beveled

adjacent faces, inner and outer braces, and bolts for securing the parts in place, substantially as described.

3. A counter made up of a series of sections, the outer brace having indentations, the inner brace and the bolts having their heads resting in the indentations, substantially as described.

4. The combination, with the counter-top having the projections E, of the counter formed with sockets F, adapted to receive the projections of the top, and the adjustable pins G, adapted to support the projections at different heights in the sockets, substantially as and for the purpose set forth.

In testimony whereof I affix my signature in presence of two witnesses.

JOHN S. DUNLAP.
